(57) **CLAIM**

The ornamental design for a construction set game piece, as shown and described.

DESCRIPTION

FIG. 1 is a top plan view of our construction set game piece;

FIG. 2 is a front perspective view thereof;

FIG. 3 is a rear view thereof;

FIG. 4 is an elevational view of the right side face thereof;

FIG. 5 is an elevational view of the left side face thereof;

FIG. 6 is a front view thereof; and,

FIG. 7 is a bottom view thereof.

FIG. 8 is a view similar to FIG. 1 of an alternative embodiment of our construction set game piece;

FIG. 9 is a front elevational view thereof;

FIG. 10 is a rear elevational view thereof;

FIG. 11 is an elevational view of the right side face thereof;

FIG. 12 is an elevational view of the left side face thereof;

FIG. 13 is a top side perspective view thereof; and,

FIG. 14 is a bottom view thereof.
